UNITED STATES PATENT OFFICE.

WILLARD W. GREEN, OF AIRLIE, OREGON.

DRIER.

1,413,908.

Specification of Letters Patent. Patented Apr. 25, 1922.

Application filed April 20, 1921. Serial No. 462,791.

To all whom it may concern:

Be it hereby known that I, WILLARD W. GREEN, a citizen of the United States, and resident of Airlie, in the county of Polk 5 and State of Oregon, have invented a new and useful Drier, of which the following is a specification.

This invention relates more particularly to drying food stuffs in the ordinary kitchen 10 oven.

The object of my invention is to provide an exceedingly simple, compact and inexpensive drying rack, and at the same time avoid the necessity of occupying space on 15 top of the stove usually required for other purposes. A further and more important object is to dry the food within the oven itself which may be closed or left partly open, and therefore not exposing the moist 20 and somewhat sticky food stuff to dust carried by the atmosphere.

I attain these results in the manner set forth in the following specification and illustrated in the accompanying drawings, 25 in which:

Figure 1 is a perspective view of my device as used in an oven, which is represented by dotted lines. Figure 2 is an enlarged vertical section through one of the 30 side frames showing the manner of supporting the trays. Figure 3 is a plan of the collapsed device of which Figure 4 is an elevation showing the manner in which the trays are nested. Figure 5 is a rear elevation 35 of the device at a reduced scale showing the method for applying side bracing if desired.

Similar numbers of reference refer to the same or similar parts throughout the several views.

Referring in detail to the drawings, I have constructed my device of two upright side walls 10 having horizontal slots 11. The metal 12 from these slots is down-turned toward the inner sides and forms ledges upon 45 which the trays rest. Between each upper and lower corner of the side walls 10 I have joined by means of the hinges 13 the ties 14 which are joined by the hinges 15. Lateral stability is secured from the hinges 13, or by 50 securing the braces 16 from the hinge 13 end of the upper tie 14 to the hinge 15 end of the lower tie 14 by any other convenient means, without departing from the spirit of my invention.

Resting on the ledges 12 are a plurality of screen trays 17 whose sides 18 diverge suffi-

ciently to permit the trays to nest compactly and have a height sufficiently great to prevent their slipping out of the slots 11. Danger of the trays catching on the ends 60 of the slots 11 during the insertion or removal of a tray is eliminated by flaring the sides 18.

I have also provided a tray 19 with a closed bottom for the purpose of catching 65 any drip from the food-containing trays and preventing same from striking the oven floor.

It will be seen that by removing all of the trays and drawing the upper hinges 15 together and the lower hinges 15 together that the two side walls 10 will come in close contact with the ties 14 folded between same. The two side walls 10 and the trays 14 are now placed in the uppermost of the trays 75 which have been nested, for convenience in shipping and storing.

The great convenience in my device lies in the fact that food stuffs ordinarily wasted for lack of time or means for preserving in 80 other ways can be saved by placing same on the trays which are adapted to fit inside of a standard oven. The oven door 20, which may be left slightly ajar or closed entirely, prevents the contact of dust carried in the 85 atmosphere, and the product is therefore much cleaner and more appetizing than where the articles are sun-dried or dried on frames set upon the stove or around the stove pipe. Furthermore, no attention need 90 be given such as carrying it in and out of doors for varying weather, as by this method the drier need not be touched unless it is desired to replace the dried food with undried food.

It will also be observed that the use of this drier in no way prevents the use of the oven itself; in fact, the drier need not be removed when using the oven to bake bread, etc. inasmuch as all of the trays can be removed if desired and the pans set down on the oven floor, or the lower tray 19, or the screen trays 17 can be inverted and placed at the desired height and used as shelves for keeping the pans off of the oven bottom.

While it is not desired to give the impression that food can be dried in the oven at the same time that baking is being done, the fact remains that owing to the fine circulation of air in the oven itself and the extreme uniformity of heat, the drying process can be narrowed down to less than

22 BEST AVAILABLE COPY 1,413,908

twenty-four hour periods for ordinary articles without subjecting same to a heat which would caramel the sugar content of the food, whereas by the sun drying process 5 the food must be labored with over a period of many days during which time mold often sets in, which renders it unfit for use and if not detected is liable to injure other food with which it comes in contact. The fact 10 must also be considered that during the fruit drying season in many sections of the country the sun is not in evidence at the time it is most desired.

I am aware that a number of driers have 15 been invented for the purpose of drying on top of a stove or near stove pipes, or in the sun, but for the reasons given above I have designed mine especially for oven use, although of course it could be used in other 20 manners if desired.

What I claim as new is:—

1. A drier consisting of two side walls, folding ties between said walls, a plurality of screen bottomed trays supported on ledges 25 on the inner sides of said walls, and a lower tray having a closed bottom adapted to catch the drip from said upper trays.

2. A drier consisting of two side walls of sheet metal having ledges on their inner sides formed by slotting said walls and 30 bending the metal inwardly, a tie hinged to each upper and lower corner of said walls, each of said ties having at its middle a hinge permitting the two walls to fold together, a plurality of screen bottomed trays adapted 35 to rest on said ledges and having diverging sides adapted for nesting, said sides having a height greater than the depth of said walls.

WILLARD W. GREEN.
